WINDOW FRAME AND STORM SASH

Erick G. Sampson, Jamestown, N. Y.

Application August 9, 1938, Serial No. 223,949

1 Claim. (Cl. 20—55)

My invention relates to windows, and it includes among its objects and advantages the provision of novel means designed to facilitate the hanging and removal of storm sashes, screens and the like.

With these and other objects in view, this invention consists in certain novel features of construction, combination and arrangement of parts to be hereinafter more fully described and claimed.

For a complete understanding of my invention, reference is to be had to the following description and accompanying drawing, in which:

Figure 1 is a sectional view of a window frame showing my invention applied thereto and illustrating the manner in which the storm sash and the like may be elevated into receiving relation with the window frame;

Figure 2 is a similar view of the window frame showing the storm sash fitted therein;

Figure 3 is a fragmentary elevational view of the structure illustrated in Figure 1; and

Figure 4 is a perspective view of one of the brackets.

In the embodiment selected to illustrate my invention, I make use of a conventional window frame 1, including the usual parting strips 2, 3 and 4 arranged to provide channels 5 and 6 for slidably supporting the upper and lower window sashes 7 and 8, respectively. Figure 2 illustrates the storm sash 9 as fitting inside the frame 1 and adjacent the parting strips 2. The storm sash 9 is of conventional construction.

To the upper run 10 of the frame 1, I mount two brackets 11 which secure the upper end of the storm sash 9 within the frame 1. Two hanger clips 12 are secured to the outer face of the storm sash 9 near its upper end for detachable connection with the brackets 11 and cooperate therewith for holding the storm sash in place.

Figure 4 illustrates one of the brackets 11. The brackets are identical in construction so that the description of one will apply to both. In Figure 4 the bracket 11 comprises a plate 13 having a right-angular extension or hook member 14 provided with a rounded outer end 15. Plate 13 includes openings 16 for the reception of screws 17 anchored in the storm sash 9.

According to Figure 4, the plate 13 carries two spaced elements 18 and 19, between which a grooved wheel 20 is rotatably mounted on a shaft 21 anchored to the elements 18 and 19. Elements 18 and 19 are located to one side of the plate 13. Hook member 14 includes a first hook 22 and second hook 23. The edge 24 is shaped to provide

a gentle incline leading from the first hook 22 up over the hook 23.

Hanger clips 12 are fixedly connected with the storm sash 9 through the medium of screws 25. The clips 12 are slotted at 26 and spaced to bring the slots into alignment with the hook members 14. To the inner face of the storm sash 9, I connect two hooks 26. Each hook includes a bowed reach 27 with the bow having its ends pressing against the sash. Each bowed reach 27 includes a threaded opening for the reception of the threaded end 28 of a bolt 29 passing through the storm sash and an opening in the hanger clip 12. Thus the hooks 26 are firmly secured in place through mere tightening of the bolt 29.

In operation a pull rope 30 is knotted at its ends, as at 31, and is slipped underneath the hooks 26 with the knots bearing against the sides of the hooks, as illustrated in Figure 3. The two runs of the looped pull rope 30 are passed over the grooved wheels 20, at which time the storm sash 9 can be elevated by pulling on the rope 30. The storm sash is elevated for bringing the slots 26 into registration with the hook members 14. As the hanger clips 12 are brought into camming relation with the rounded ends 15 of the hook members 14, the hanger clips will ride over the rounded ends and slide inwardly of the first hook 22 for connecting the hanger clips with the hook members.

Figure 1 illustrates the upper sash 7 as being lowered for accommodating the pull rope 30 so that the storm sash may be elevated from a position inside the building. After the hanger clips 12 have been connected with the hook members 14, the pull rope is disconnected from the hook 26. At this time the storm sash is manually manipulated for moving the hanger clips 12 beyond the second hooks 23 after which the lower end of the storm sash is pulled into place inside the frame 1 and may be made secure in the usual manner as through the medium of hooks or the equivalent fastening devices. The second hooks 23 are so located as to effectively support the upper end of the storm sash 9 in pressure relation with the sealing strip 2.

In removing the storm sash 9, the sash is lifted for bringing the hanger clips 12 out of holding relation with the second hooks 23, after which the sash is moved outwardly on the hanger members 14 to the dotted line position of Figure 2. With the upper sash 7 lowered, the ends of the pull rope 30 are easily connected with the hooks 26 and passed over the grooved wheels 20 to per-

mit lowering of the storm sash through the medium of the pull rope.

While the present invention has been described in connection with the storm sash, the invention is equally well adapted to screens. The invention is applicable to window structures of conventional design and provides a convenient system for hanging storm sashes and the like as well as removing the same.

10. What is claimed is:

In combination with a window frame, a sash detachably connected with the frame, brackets carried by the window frame exteriorly of the room at the top of the frame, said brackets including hooks and pulleys, slotted clips attached to the upper margin of said sash, a pull line con-

nected with the upper margin of the sash for elevating the latter, said pulleys being so arranged with respect to said hooks as to elevate the sash with the clips thereon positioned so as to engage the hooks, and cam means on said hooks for engaging said clips to move the latter and the sash outwardly for bringing the slots in the clips into registration with the hooks so that a continued pull on the pull line will move the clips inwardly of the hooks to be retained thereby upon giving slack to the pull line, said brackets being provided with second hooks for connection with said clips to hold the sash in assembled relation with said frame.

ERICK G. SAMPSON.
